UNITED STATES PATENT OFFICE.

CLARENCE H. FLINT, OF FLUSHING, NEW YORK, ASSIGNOR TO GENERAL CHEWING GUM CORPORATION, OF BROOKLYN, NEW YORK, A CORPORATION OF NEW YORK.

PROTECTOR FOR CONFECTIONS, ETC.

Application filed June 24, 1926. Serial No. 118,395.

One object of my invention is to provide a simple but attractive device for covering boxes of candy, gum, drugs and other package merchandise, and protecting them, and 5 at the same time displaying them to customers.

Another object is to provide in connection with such a device convenient means for receiving and holding articles for the convenience of the customers or the merchant and at 10 the same time prevent theft or pilfering of the merchandise.

Another object is to facilitate the raising and lowering of the device and the placing of 15 it in position over the box.

In the preferred form of the invention, the entire device is formed of a single casting or mould of glass with a recess in its lower rear face adapted to fit over the open upper 20 edge of a box and a pocket or groove of some sort in its upper front edge, all constructed and arranged so that the device may be readily raised for the purpose of access to the box or so that the box may be drawn out from the 25 side or rear of the device.

Figure 1 is a longitudinal sectional view of a device involving my invention showing it resting on a support and covering a box.

Figure 2 is a side view showing the device 30 being raised to permit access to the box.

Figure 3 is a plan view of the device.

The body 5 is provided with a recess 6 open at the bottom and adapted to fit over a box 7 containing the articles to be displayed. The 35 inner side walls of this recess are preferably provided with inclined lugs or ribs such as 8 and 9 for assisting in positioning the device over the box and at the same time insuring a fairly snug fit for the upper edge of the box 40 to keep out dust and insects.

The front of the device is provided with an extension 10 hollowed out to form a pocket 11 in its upper surface. A web 12 preferably connects the extension with the body for reinforcing purposes. The upper surface of the 45 body is preferably inclined downward and forwardly so that articles dropped upon it will slide down into the pocket 11. The part 13 may be formed as a lens to magnify the 50 articles in the box. I prefer that the entire device be formed of a single piece of transparent glass so that the purchaser can see not only

the contents of the box through the top but so that he can also see the sides of the box which are usually provided with trademarks, advertising legends, etc. At any rate the upper part 13 should be transparent.

To facilitate the raising and lowering of the device I preferably provide a depending rib 14 beneath the extension 10 and near the front 60 end, and I also provide a ledge or rib 15 at the rear serving as a thumb-piece or handle. The operation and use of this rib 14 and the handle 15 will be obvious from an inspection of Figure 2. The rib 14 serves as a fulcrum for 65 positioning the device so that when it is lowered again it will come down into its proper position over the box without crushing or displacing the box.

I claim:

1. A merchandise cover and protector comprising a transparent glass body provided with a recess in its lower rear part adapted to receive a box and an open pocket in the upper front part, the wall over the recess being 75 formed as a magnifying lens.

2. A combined change receiver and merchandise protector comprising upstanding connecting walls arranged to enclose an article of merchandise on all sides and protect 80 the same from dust, a cover from which said walls depend, a handle projecting from one of said walls, said cover sloping beyond the side opposite said handle to form a change receiving recess attached to said merchandise 85 protector, said cover being transparent at least substantially between said upstanding walls.

3. A combined change receiver and merchandise protector comprising upstanding 90 connecting walls arranged to enclose an article of merchandise on all sides and protect the same from dust, a cover from which said walls depend, a handle projecting from one of said walls, said cover sloping beyond the 95 side opposite said handle to form a change receiving recess attached to said merchandise protector, said cover being transparent at least substantially between said upstanding walls, a web connecting the under side of the adjacent receiver wall and upstanding wall, and a supporting lug below said receiver contiguous the plane of the ends of said upstanding walls, the outer wall of said change receiver 100

remote from said protector being rounded to permit the receiver and protector to roll thereon when the handle is raised an amount to move the receiver off its lug.

5. A change receiver having a recess, a support therefor located to one side of said receiver and comprising upstanding connected

walls arranged to enclose an article of merchandise, a transparent cover connecting the top of said walls and a projection on said support for rocking the same about a receiver wall.

CLARENCE H. FLINT.
